United States Patent Office.

WILLIAM ROBINSON, OF BROOKLYN, NEW YORK.

Letters Patent No. 78,539, dated June 2, 1868.

IMPROVEMENT IN LAMP-BURNERS.

The Schedule referred to in these Letters Patent and making part of the same.

TO ALL WHOM IT MAY CONCERN:

Be it known that I, WILLIAM ROBINSON, of Brooklyn, in the county of Kings, and State of New York, have invented certain new and useful Improvements in Lamp-Burners; and I do hereby declare that the following is a full, clear, and exact description of the same, reference being had to the accompanying drawings, making a portion of this specification, in which—

Figures 1, 2, and 3 are central vertical transverse sections, showing the several forms or modifications of my invention.

Figures 4, 5, and 6 are plan views of the same.

Similar letters of reference indicate corresponding parts in all the figures.

It frequently occurs in so-called kerosene-burners, that the oil is drawn up the wick-tube in excess of the quantity required to supply the flame, in which case the excess or surplus of oil runs down the exterior of the aforesaid tube, and besmears the burner and the lamp to which it is attached; and furthermore, that the condensation of vapors rising from the lamp upon the internal surfaces of the burner, produces a like result.

The object of this invention is to obviate these objections, and to this end it consists in the formation of a trough-like collar around the space between the wick-tube and the top of the burner, whereby the proper passage of the surplus oil to the body of the lamp is more effectually secured than would otherwise be the case.

The invention further consists in a detachable external trough, whereby the products resulting from the condensation of vapors within the burner may be prevented from dripping over the external surface of the body of the lamp, and which may be applied to any ordinary form of burner.

To enable others to understand the nature and construction of my invention, I will proceed to describe it with reference to the drawings.

The base or lower portion of the burner is shown at A, and is provided with the vertical wick-tube B, of any suitable construction. The cap or cone of the burner, of any appropriate form, is indicated at C.

Formed in the top plate *a* of the base, A, upon each side of the wick-tube, is a narrow opening or slot, *b*, which enables such oil as may flow or drip down the same to pass downward through the base to the body of the lamp, upon which the said base may be secured, the bottom plate *c* of the base being furnished with suitable holes, *c'*, in order that the said oil may pass freely therefrom, any spreading of the surplus oil from the wick-tube upon the various parts of the burner, and thence to the exterior of the lamp, being thus, in a great measure, guarded against. In order to render still more certain the passage of the surplus oil just mentioned through the openings *b*, a trough, *f*, is placed around the wick-tube, and at the outer edges of the openings, in such manner that in case any of the surplus oil should fall upon or come in contact with the flaring or sloping sides thereof, it will be directed downward to the openings, and thus caused to pass through the same. This trough may be made detachable, and extended above the top plate *a*, with the lower edges of its sides fitted into the outermost portions of the openings *b*, as shown in figs. 1 and 4; or it may be formed by bending downward, into an inclined position, those parts of the aforesaid top plate adjacent to the openings, as represented in figs. 2 and 5, care being taken, in this case, to depress those parts of the plate *a* at the narrow edges of the wick-tube, in such manner as to form channels *a'*, which will guide to the openings such oil as may pass down the edges aforesaid. It is found that the vapors rising from the oil in the lamp, when the latter is not in use, condense upon the internal surfaces of the burner, and dripping down through the perforated sides of the said burner, pass to the external surface of the said lamp; and in order to obviate this, an annular trough, *D*, is so fitted upon the burner as to intercept the condensed matter just mentioned, as it passes down, as just hereinbefore set forth, the said trough being made preferably with a flat internal flanch, which is fitted between the collar *g* of the lamp and the base of the burner, in such manner as to be securely retained in place, at the same time that it is capable of being very readily detached therefrom when desired, as, for instance, when it is required to clean the same.

What I claim as my invention, and desire to secure by Letters Patent, is—

1. The trough, *f*, arranged in relation with the openings *b*, at the sides of the wick-tube, substantially as and for the purpose specified.

2. The annular trough *D*, made detachable, and constructed with the internal flanch, whereby it may be fitted between the burner and the lamp, substantially as and for the purpose specified.
